FIRE ARM

Alex Seidel, Oberndorf-on-the-Neckar, Germany,
assignor to Mauser-Werke A.-G., Oberndorf-
on-the-Neckar, Germany, a joint-stock com-
pany of Germany

Application August 20, 1935, Serial No. 37,078
In Germany August 10, 1934

7 Claims. (CL 42-4)

My invention relates to fire arms, and particularly to automatic pistols with hammer and trigger. The object of my invention is to improve the trigger mechanism, and to provide suitable safety devices for the trigger and firing mechanisms.

The improved trigger mechanism according to my invention is so designed that it is assembled and inserted in the arm, and removed from the arm, and disassembled simply, rapidly and without any extra tools and fastening members such as screws and the like.

It is still another object of my invention to provide an improved magazine lock which, known per se cooperates with the push rod for the hammer. This is effected by combining the push rod, the cocking spring and the magazine lock into a unit, insertion and removal of which are facilitated, and which cannot be inserted in a wrong position.

The invention will now be described and illustrated.

In the drawings

Fig. 1 is a section of the stock of a pistol showing its trigger mechanism in elevation.

Fig. 2 is a section on the line A—B in Fig. 1, viewed in the direction of the arrows.

Fig. 3 is an elevation of a connecting rod between the trigger, or its pawl, and the hammer, of a pistol.

Fig. 4 is a plan view of the connecting rod.

Fig. 5 is an axial section of a pistol equipped with the connecting rod illustrated in Figs. 3 and 4, with its hammer uncocked.

Fig. 6 is a section which is similar to the section in Fig. 5 but shows the hammer after it has been cocked by pulling the trigger, and is just about to become disengaged from the connecting rod.

Fig. 7 is a longitudinal section of a pistol showing the safety means by which firing by a blow or the like on the hammer is prevented, the parts being shown in safety position, and

Fig. 8 shows the parts illustrated in Fig. 7 in firing position.

As mentioned, it is one of the objects of my invention to provide a trigger mechanism which is simple and does not require auxiliary tools and extra fastening means for assembling and inserting, and for disassembling and removing it. The problem is to combine the parts of the trigger mechanism into a self-contained unit which is easily inserted and removed. The parts are so designed and arranged that the unit is held assembled by other detachable parts of the arm. In

an automatic pistol, this is effected by the stock and the breech, or by the stock and the barrel.

This problem is solved according to the invention by placing the trigger mechanism in a frame which is inserted in a suitable recess of the pistol, so that, when the pistol or other arm is closed, the parts of the mechanism are held against displacement from their positions.

Referring now to the drawings, and first to Figs. 1 and 2, the stock 1 of a pistol has a recess 2 which is exposed at its top by removing the barrel 3. A frame 4 is inserted in the recess 2. The frame has two side plates 5 connected by a transverse member 6 at their front ends which bear against the inner walls of the recess at 7. Each side plate 5 has a downwardly projecting lug 8 and 9 whose ends 8 and 9 engage corresponding faces 10 and 11 of the recess in the stock. By this means, the frame 4 is held against displacement in axial and transverse direction. The lower faces of the side plates 5 are supported by the bottom plate 12 of the recess.

The frame 4 is inserted from the top, after the barrel and the breech have been removed. One of the side plates 5 (at the left in Fig. 2) is higher than the other, and its top 13 engages below the lower face of the barrel 3, so that the frame 4 is held against vertical displacement. Obviously, the breech, or any other part of the arm might be used for holding the frame 4 in the stock.

The frame 4 is open at its rear end, opposite the transverse member 6. A trigger 14 and the trigger spring 15 are inserted from the rear between the side plates 5, and the trigger pin 16 is inserted through suitable bores in the trigger 14 and the lugs 17 by which the side plates are anchored at 10 and 11, as described. The trigger spring 15 has a coiled central portion through which the trigger pin 16 is threaded. The ends of the trigger pin are flush with the outer faces of the side plates 5 and, since the pin is without any projections, it is not held against axial displacement before the frame is inserted in the recess 2, and the pin is restrained by the inner faces 7 of the recess, as shown in Fig. 2.

The trigger 14 is so designed that it makes a perfectly tight seal in the casing of the arm at its lower side. In the position illustrated in Fig. 1, a projection at the front face of the trigger bears on the underside of the stock below the face 11. The rear end 18 of another projection at the rear face of the trigger 14 is opposite an edge of an opening in the stock. In order to effect a tight seal in all other positions of the trigger, curved faces 19 and 20 are provided whose curvatures

have the axis of the trigger pin 16 for their centre. When the trigger is rocked about its pin 16, the curved faces 19 and 20 are always in sealing relation to the mating faces of the stock.

5 The rod 22 is pivoted to an upward extension of the trigger 14 at 21. The connection of the rod and trigger may be separated when the frame 4 is removed, or the connection may be permanent so that the frame, the trigger, and the connecting 10 rod are removed together.

Figs. 1 and 2 show the old design of the connecting rod 22. As mentioned, it is one of the objects of my invention to provide an improved connecting rod which eliminates tilting and all 15 other causes of increased resistance against the pulling of the trigger. My improved connecting rod is a double fork. It has a pair of long arms projecting from the front, and a pair of short arms projecting from the rear of a transverse 20 web. The two long arms embrace the stock and hold the rod against tilting during the pulling of the trigger. The short arms embrace the hammer and are equipped with hooks engaging shoulders on the hammer. By these means, all tilting forces 25 are eliminated in the transmission from the trigger to the hammer.

A forked connecting rod according to my invention is shown in Figs. 3 and 4, and Figs. 5 and 6 show a pistol equipped with such a rod.

30 26, Figs. 3 and 4, is the transverse web of the double-fork connecting rod 22. The long arms of the fork at the front embrace a web of the stock 1. The longer one of the two long arms is connected to the trigger extension at 21. Its 35 front end projects beyond the pivot 21 and has a forwardly inclined wedge face 31. The lower end of the wedge face is engaged by the vertical rear end of a slide 30, Figs. 5 and 6, and a trigger spring 29 acts on the vertical front end of the 40 slide. The point where the slide 30 engages the wedge face 31, is below the pivot 21 so that the pressure of the spring 29 causes the connecting rod to turn about the pivot so that its rear end is elevated. The rear end has the two short 45 arms 32 whose hooks 33 engage shoulders 34 on the hammer 37. A spring catch 35 which is fulcrumed on the pistol for cooperation with the hammer 37, engages between the long arms in front of the web 26. The pressure of the trigger 50 spring 29 forces the hooks 33 against the shoulders 34, Fig. 5, or the web 26 against the lower end of the catch 35, Fig. 6. The short arms 32 embrace the hammer 37 symmetrically in the 55 position illustrated in Fig. 5, and the spring catch 35 projects between the long arms in the position illustrated in Fig. 6. In both cases, the transmission of the forces is symmetrical, or central, and there is no tilting of the connecting rod, with increased resistance.

60 Controlling abutments 36 are presented by the two longer arms of the connecting rod and engaged by the two shoulders 34 of the hammer 37 when it is cocked by hand. The connecting rod 22 is pushed forward and, when the hammer is 65 cocked, the web 26 is in close vicinity of the lower end of spring catch 35, Fig. 6. Since the trigger is also moved into active position by its connection 21 to the rod 22, the distance through which the trigger is pulled for firing, is quite short.

70 Safety against the firing of two cartridges in succession, and against operation when the pistol breech is not fully closed, is obtained in known manner by cooperation of the breech and the connecting rod. If the breech is not in closing 75 position, the connecting rod is moved beyond

reach of the spring catch 35 and the hammer 37, so that, if the operator still holds the trigger after a cartridge has been fired, the spring catch 35 is not permanently held beyond reach of the hammer, so that firing in succession is prevented, 5 while the hammer 37 can neither be cocked nor operated by the trigger when the breech is not closed.

The longer one of the two long arms has a lug 38 which engages in a recess 39 of the breech 40, 10 Figs. 5 and 6.

Means will now be described with reference to Figs. 7 and 8 by which unintentional operation of the hammer is prevented. Such unintentional operation may occur if a blow strikes the un- 15 cocked hammer, or if the cocked hammer is released without operation of the trigger. Fig. 7 shows the hammer 37 in uncocked position in which the hammer spring 126 holds the striking face of the hammer at a distance c from the rear end of the firing pin 128. The trigger 14, the connecting rod 22, and the spring catch 35 have already been described. When the trigger is pulled, Fig. 8, a hook 68 at the rear end of the connecting rod 22 engages the lug 60 on the 25 catch 35 and moves the catch out of engagement with the hammer. 135 is the spring of the catch 35.

The spring catch 35 is operatively connected to a locking bellcrank 129a which is positioned in a 30 recess 127 of the stock 1. The free end of the bellcrank is opposite a lug 134 on the hammer 37 when the trigger 14 has been released, Fig. 7, and the spring catch 35 has been moved into arresting position by its spring 135. A blow on 35 the non-cocked hammer 37 causes the lug 134 to strike the free end of the bellcrank 129a whereby the hammer is stopped before it reaches the end of the firing pin 128. This removes any danger from a blow on the hammer. The bell- 40 crank, however, not only prevents striking of the hammer against the firing pin when a blow is exerted on the hammer but absolutely prevents unintentional operation of the firing pin, whatever may be the position of the hammer. For 45 instance, if the pistol is dropped, the cocked hammer might become disengaged from the catch 37. The hammer now strikes, but the catch 35 is returned into arresting position immediately, and so its bellcrank 129a intercepts 50 the hammer 37 before it reaches the firing pin 128.

The hammer is only ready for firing when the trigger 14 is pulled, as shown in Fig. 8. The connecting rod 22 rocks the spring catch 35 by its 55 lug 60 until the lug 134 of the hammer is cleared by the bellcrank 129a, so that the hammer is not interfered with in its operation of the firing pin 128. The spring catch 135 is held disengaged from the hammer and its bellcrank 129a is held out of 60 reach of the lug 134, until the cartridge has been fired and the breech, in its backward movement, separates the connecting rod 22 and the spring catch 35.

I claim:

1. A fire arm comprising a hollow stock, a frame 65 capable of being inserted into and removed from the cavity of the stock through an opening therein and having side plates of which one is higher than the other, said cavity being shaped to hold the 70 inserted frame against movement in any direction except that of removal, a trigger pivoted in said frame and removable therewith through the opening, and means cooperating with the higher side plate for closing the opening and forming the 75

sole means for completing the fixation of said frame in said cavity.

2. A fire arm comprising a hollow stock, a frame with side plates capable of being inserted into and removed from the cavity of the stock through an opening in the top of the latter, one of said side plates being higher than the other, seatings formed in the cavity of the stock holding the inserted frame against movement in any direction except that of removal, a trigger pivoted in the side plates of the frame, and an operative part of the fire arm closing the opening in the stock and completing the fixation of the frame in the cavity thereof by means of said higher side plate.

15. 3. A fire arm comprising a hollow stock, a frame with side plates capable of being inserted into and removed from the cavity of the stock through an opening in the top of the latter, one of said side plates being higher than the other, seatings formed in the cavity of the stock holding the inserted frame against movement in any direction except that of removal, a trigger, a pin insertable axially through transverse bores in the side plates of the frame to form the pivot of the trigger, said pin when the frame is in the cavity being held against axial shifting by the sides of the cavity, and an operative part of the fire arm closing the opening in the stock and completing the fixation of the frame in the cavity thereof by means of said higher side plate.

20. 4. A fire arm comprising a hollow stock, a trigger and a hammer pivotally mounted in the stock, a connecting rod enabling the hammer to be cocked and fired by trigger operation, said rod comprising a bridge piece and two pairs of parallel arms connected by the bridge piece, a pivotal connection between the trigger and said rod, connections rendered operative by rocking movements of the connecting rod between one of its 25 pairs of parallel arms and the hammer, and guide means engaging between the parallel arms of the other pair of arms to ensure fixation of the plane of said rocking movement.

25. 5. A fire arm comprising a hollow stock, a trigger and a hammer pivotally mounted in the stock, a connecting rod enabling the hammer to be cocked and fired by trigger operation, said rod

comprising a bridge piece and two pairs of parallel arms connected by the bridge piece, a pivotal connection between the trigger and said rod, connections rendered operative by rocking movements of the connecting rod between one of its 5 pairs of parallel arms and the hammer, guide means engaging between the parallel arms of the other pair to ensure fixation of the plane of said rocking movement, and a spring catch for holding the hammer cocked, said catch co-operating with the bridge piece of the connecting rod to release the hammer upon firing.

6. A fire arm comprising a hollow stock, a trigger and a hammer pivotally mounted in the stock, a connecting rod enabling the hammer to be cocked and fired by trigger operation said rod comprising a bridge piece and two pairs of parallel arms connected by the bridge piece, a pivotal connection between the trigger and said rod, connections rendered operative by rocking movements of the connecting rod between one of its 15 pairs of parallel arms and the hammer, guide means engaging between the parallel arms of the other pair of arms to ensure fixation of the plane of said rocking movement, a spring catch for holding the hammer cocked, said catch co-operating with the bridge piece of the connecting rod to release the hammer upon firing, abutment means on the connecting rod near said bridge piece, and a heel on said hammer co-operating 20 with said abutment means to cause the bridge piece to approach the spring catch when the hammer is cocked manually.

7. A fire arm comprising a stock, a hammer and a trigger mounted therein, a spring catch for holding the hammer in cocked position, an arm on the spring catch normally obstructing full firing stroke of the hammer, and a connecting rod operable by the trigger to move the spring catch into a position in which it releases the hammer and 35 also carries the arm out of hammer obstructing position, said connecting rod being in the form of a double fork with a pair of long arms cooperating with the trigger and a pair of short arms cooperating with the spring catch.

ALEX SEIDEL.
